UNITED STATES PATENT OFFICE.

WILLIAM H. CRAIG, OF SYRACUSE, NEW YORK, ASSIGNOR TO E. C. STEARNS & CO., OF SAME PLACE.

LOOM-SHUTTLE.

SPECIFICATION forming part of Letters Patent No. 545,196, dated August 27, 1895.

Application filed August 5, 1890. Serial No. 361,118. (No model.)

To all whom it may concern:

Be it known that I, WILLIAM H. CRAIG, a citizen of the United States, residing at Syracuse, in the county of Onondaga and State of New York, have invented a new and useful Improvement in Loom-Shuttles, of which the following is a specification.

This invention relates to that class of shuttles which are used in looms for weaving heavy fabrics—for instance, wire-cloth.

The object of this invention is to improve the means whereby the cop or bobbin is held against longitudinal movement in the shuttle, and whereby the tension of the shuttle-thread is regulated.

In the accompanying drawings, Figure 1 is a longitudinal sectional elevation of a shuttle provided with my improvements. Fig. 2 is a top plan view thereof. Fig. 3 is a horizontal longitudinal section of the shuttle. Figs. 4 and 5 are vertical sections in lines *xx* and *yy*, Fig. 3. Fig. 6 is a vertical cross-section in line *zz*, Fig. 1.

Like letters of reference refer to like parts in the several figures.

A represents the body of the shuttle, which is provided at its ends with the usual metallic heads *a a* and with a longitudinal cavity *B* for the reception of the wire cop or bobbin *C*. The bed is provided in its bottom with two rows of upwardly-projecting teats or pins *c*, which embed themselves in the lower side of the wire-cop when the latter is placed in the bed of the shuttle. The top of the bed *B* is closed by a spring-plate *D*, which is secured to the shuttle-body by transverse straps *d*, secured to the upper face of the shuttle, or by other suitable means. The spring-plate is provided with a longitudinal slot *E*, which is bordered by two rows of teeth or serrations *e*, which are preferably formed integral with the spring-plate by stamping them out of the body of the spring-plate and bending them downward. These teeth become embedded in the upper side of the wire-cop and hold the latter down upon the teats in the bottom of the bed, whereby the wire-cop is securely held against longitudinal movement in the shuttle-bed. One end of the bed *B* is preferably

made cone-shaped, as shown at *g*, to receive 50 the conical end of the wire-cop.

H represents an oblique opening or passage extending from the conical seat through the shuttle-body for the purpose of affording access to the shuttle-thread. The conical seat 55 and a portion of the passage *H* are preferably lined with metal, as shown, to reduce the wear on these parts.

J represents an antifriction or guide roller pivoted vertically in the passage in rear of 60 the cop-seat. This roller is preferably pivoted by means of a bolt *j* and nut *j'*, as shown in Fig. 4.

K represents the eye of the shuttle, and *L* a longitudinal passage formed in the inner side 65 of one of the vertical walls of the shuttle, whereby the eye is placed in communication with the oblique passage *H*. The wire in unwinding from the cop or bobbin passes outwardly through the hollow center of the same 70 and into the passage *H* in rear of the cop-seat, thence around the antifriction-roller *J* and inwardly through the passage *L*, and thence out through the eye *K*.

The eye *K* is provided with two tension-rollers *M N*, whereby the tension on the shuttle-thread is regulated. These rollers are arranged vertically, and one of them is journaled in fixed bearings *m*, while the other is adjustable toward and from the fixed roller. 75 80

n represents an adjustable plate arranged on the upper side of the shuttle and secured thereto by a screw *o*, passing through a slot *p* formed in the plate. The latter is provided with a depending arbor *q*, which supports the 85 movable roller. Upon unscrewing and removing the adjustable plate carrying the depending arbor, the roller can be removed from said arbor and another roller of greater or less diameter can be put in its place. When 90 the shuttle is traveling toward the right in the direction indicated by the arrow in Fig. 3, the shuttle-thread bears against the inner side of the adjustable tension-roller *N* and the outer side of the fixed tension-roller *M*, and 95 the tension is controlled by the bend which the thread receives in passing around these rollers and from one roller to the other. In

order to increase the tension on the wire when the shuttle is moving in this direction, the adjustable tension-roller is moved toward the fixed roller, which causes a sharper turn in the wire. When the shuttle moves in the opposite direction, the shuttle-thread in leaving the shuttle-eye passes only around the adjustable roller N, as indicated by the dotted lines R in Fig. 3, and the tension is regulated by the diameter of the adjustable roller. A large adjustable roller creates a comparatively large bight in the wire, which produces a moderate tension on the thread, whereas a smaller roller forms a more abrupt bend in the wire and creates a correspondingly greater tension. In order to increase the tension on the wire in both directions, it is therefore necessary to provide rollers of various diameters, either of which can be placed upon the removable arbor, as may be necessary to produce the desired tension. When the cop or bobbin is placed in the bed of the shuttle, the teats on the bottom will engage between the strands of wire. The covering-plate D is introduced under the fastening-straps d by springing it upwardly at the center, so that the ends of the plate will be drawn together and permitted to enter under these straps. The spring-plate is continually in a strained condition, so that its prongs will bear constantly on the top of the cop. By holding the cop against longitudinal movement in the shuttle the danger of tangling or breaking the wire is avoided. It also permits a cop of much larger capacity or weight to be employed, because there is no danger of the wire being broken by the loose portion of a heavy cop moving back and forth in the shuttle-bed. This effects a great sav-

ing in time, because less stoppages of the loom are required for renewing the cop in the shuttle.

I claim as my invention—

1. The combination with the shuttle body having an eye through which the shuttle thread passes, of two tension rollers arranged in said eye, a support on which one of said rollers is mounted capable of movement on the shuttle body toward and from the other roller, and means whereby said support is secured in its adjusted position, substantially as set forth. 45

2. The combination with the shuttle body having an eye through which the shuttle thread passes, of a tension roller mounted on a stationary bearing in said eye, a roller support capable of movement on the shuttle body toward and from the stationary roller, a tension roller removably mounted on said support, and means whereby said support is secured in its adjusted position, substantially 60 as set forth. 55

3. The combination with the shuttle body having an eye through which the shuttle thread passes, and a tension roller arranged in said eye, of a plate provided with an arbor projecting into said eye and capable of movement toward and from said roller, a removable tension roller mounted on said arbor, and means whereby said plate is secured in its adjusted position, substantially as set forth. 70 65

Witness my hand this 31st day of July, 1890.

WILLIAM H. CRAIG.
